UNITED STATES PATENT OFFICE.

JAMES R. FLEMING, OF SCRANTON, PENNSYLVANIA.

CAR SUSPENSION.

Application filed March 30, 1922. Serial No. 548,015.

To all whom it may concern:

Be it known that I, JAMES R. FLEMING, a citizen of the United States, and a resident of Scranton, in the county of Lackawanna and State of Pennsylvania, have invented certain new and useful Improvements in Car Suspension, of which the following is a full, clear, and exact description.

This invention relates to car and truck 10 mountings and in particular to mine cars wherein the body of the car is carried by a journal box which fits the axle.

A particular object of the invention is to provide in conjunction with the journal box 15 a relatively "floating" bearing plate to which is attached the sill or bolster common in the mine type of car or truck.

A further object is the provision of means for preventing undue compression stresses to 20 occur in the springs or pounding or hammering thereof due to the roughness of track which is characteristic of mines.

A still further object is to provide a method of thoroughly lubricating the interior 25 of the journal box.

Drawings.

Figure 1 is a front elevation of my improved mounting, showing the bearing plate 30 and spring housing members which move relatively to the journal box.

Figure 2 is a top plan view, partially in section of the mounting as seen in Figure 1, the sill of the car being omitted and a 35 portion of the bearing plate being removed to expose one of the spring elements.

Figure 3 is a vertical section taken on the line 3-3 of Figure 1 showing the interior construction of the journal box.

Figure 4 is a transverse section taken on the line 4-4 of Figure 2, and shows the journal box and its position relatively to the spring suspension members.

Description.

Referring to the drawings in detail, 45 10 denotes a car axle which carries at its end a wheel, the hub 11 of which only is shown. A portion of the hub 11 and axle 10 are 50 disposed within the journal box 12 which is of the same shape substantially as the one shown and described in my copending application, filed March 30th, 1922, and serially numbered 548,014, now Patent No. 1,451,690, 55 granted April 17, 1923, reference to which is here made.

The journal box comprises a roller bearing element 13 and its liner 14, the box being formed at its top, centrally of said bearings, to provide a lubricating reservoir 15, 60 said reservoir being formed in an extended round topped knob or boss 16, and supplied with lubricant through a bore 17 which extends through one of a pair of oppositely disposed guide forming extensions 18 cast 65 in the exterior of said journal box.

The end of the journal box is closed with a cover 19 in which are the axle engaging packing glands 20, a pair of which, in the forward part of the box, bear on the axle 70 10 and wheel hub 11 to prevent the escape of lubricant from the bearings 13.

The guides 18 are disposed centrally of said journal box and at the bottom of the latter and centrally of the guides there is 75 cast integral with the box, the spring supporting arms 21 which are cupped as at 22, the bottoms of the cups being rounded as at 23 to provide a self-centering means for the washers 24 disposed therein. 80

A bearing plate 25 overlies the journal box 12 and is bolted or riveted as at 26 to the side sill or bolster 31 of the car which may be of wood or metal. This bearing plate 25 is formed to provide dependent 85 spring housings 27 which fit slidably into the guides 18 and have cast therein spring centering cups 28 over which the springs 29 fit. The springs rest upon the washers 24 of the journal box arms and carry the bearing plate 25 in spaced relation with the journal box 12.

The side walls of the housings 27 extend slightly below the arms 21 and have passed therethrough bolts 30 which underlie said 95 arms and prevent separation of the journal box and bearing plate.

It will be noted that there is a space between the under side of the bearing plate 25 and the top of the knob or boss 16. This 100 space is a trifle less than the accumulated spaces between the springs, so that when the car is overloaded and the springs close, they will be prevented from entirely closing because the plate 25 will be then resting upon the boss 16 and the weight will be transmitted directly to the journal box 12. This arrangement prevents strain on the springs 29, as it is well known that undue compression and hammering thereof will cause loss 110 of temper and eventually breakage.

The view shown in Figure 4 best illus-

trates the relative positions of the parts and it is assumed that the positions are taken as at normal or average load. There is thereby provided a floating journal box and the springs will take up any unevenness in the track, thereby eliminating undue wear on the truck and journal box parts. The journal box will be rendered self-aligning when the bearing plate rests upon the round-topped boss.

Claims.

1. In a car mounting of the character described, an axle; a journal box therefor; extensions on said journal box; a bearing plate on said car; springs adapted to maintain said plate and said journal box in spaced relation; and means whereby said springs will be rendered self-centering.
  2. In a car mounting of the character described, an axle, a journal box for said axle, a bearing plate on said car, spaced housings depending from said plate, guides formed with said journal box and arranged in sliding engagement with and between said housings, springs disposed within said housings and adapted to maintain said journal box in spaced relation to said plate, and means cooperative with said springs whereby the same are rendered self centering.
  3. In a car mounting of the character described, an axle, a journal box for said axle, springs adapted to maintain said journal box in spaced relation to the body of a car, and means cooperative with said springs whereby the same are rendered self-centering.
  4. In a car mounting of the character described, an axle, a journal box for said axle, a bearing plate on said car, spaced housings depending from said plate, guides formed with said journal box and arranged in sliding engagement with and between said housings, springs disposed within said housings and adapted to maintain said journal box in spaced relation to said plate, and means carried by said journal box and cooperative with the lower ends of said springs whereby the springs are rendered self-centering.
  5. In a car mounting of the character described, an axle, a bearing plate on said car,
- spaced housings depending from said plate, a journal box slidably movable vertically between said housings, extensions formed on said journal box and under-lying the lower ends of said housings, springs disposed within said housings and interposed between the opposite ends of said plate and said extensions and adapted to maintain said journal box spaced from the plate, means formed with said journal box and cooperative with said plate whereby the journal box is rendered self aligning, and means cooperative with the extensions of said journal box whereby said springs are rendered self-centering.
6. In a car mounting of the character described, an axle, a bearing plate on said car, spaced housings depending from said plate, a journal box slidably movable vertically between said housings, extensions formed at the opposite ends of said journal box and under-lying the lower ends of said housings, springs disposed within said housings and interposed between the opposite ends of said plate and said extensions adapted to maintain said journal box normally spaced apart from the plate, means formed with said journal box and cooperative with said plate whereby the journal box is rendered self-aligning, and means cooperative with the extensions of said journal box and the lower ends of said springs whereby the latter are rendered self-centering.
7. In a car mounting of the character described, a bearing plate on said car, a journal box supported beneath said bearing plate and arranged to have relative movement with respect thereto, springs interposed between said bearing plate and said journal box for normally retaining the latter in spaced relation with respect to the former, seats having convexed bottom walls carried by said journal box for the reception therein of the lower ends of said springs, and members interposed between the lower ends of said springs and the convexed bottom walls of said seats whereby to render the springs self-centering.

JAMES R. FLEMING.
